UNITED STATES PATENT OFFICE.

EDWARD J. KERNS, OF WORCESTER, MASSACHUSETTS.

EXERCISING-MACHINE.

1,139,126.

Specification of Letters Patent. Patented May 11, 1915.

Application filed December 30, 1914. Serial No. 879,647.

To all whom it may concern:

Be it known that I, EDWARD J. KERNS, a citizen of the United States, residing at Worcester, in the county of Worcester and 5 State of Massachusetts, have invented certain new and useful Improvements in Exercising-Machines, of which the following is a specification.

My invention relates to an exercising machine, and to that type of exercising machines in which cords, with handles attached, are used, and in which the cords are drawn out under tension, by the operator, and then returned automatically to their 15 first position.

The object of my invention is to provide an improved exercising machine of the type referred to, which is portable, and which may be set up and readily attached to the 20 floor, or wall of a room, and the operation of the machine may be regulated, so that it may be used by young persons, or by grown up persons.

A further object of my improved exercising machine is to adapt it to be combined with, and used in connection with a detached cockpit of a rowing boat, having a sliding seat, and foot holders, so that my exercising machine may be used as a rowing machine.

My invention consists in certain novel features of construction of my exercising machine as will be hereinafter fully described.

In my improved exercising machine, I provide preferably two rotary wheels or drums, each having a cord wound around the same, with one end attached thereto and the other end provided with a handle, and each drum has its hub mounted on a shaft, and one end of a spring is connected with 35 the drum, and the other end of said spring is connected with a stationary part of the frame of the machine, said spring preferably extends within an annular chamber formed on the frame, and extends around 40 the hub and within the periphery of the drum, and acts to control the rotary motion of the drum. In connection with each rotary drum, a friction strap, preferably encircling a side flange on the rotary drum 45 may be used, to increase the tension on the drum, all as will be hereinafter fully described.

Referring to the drawing: Figure 1 is a plan view of an exercising machine embodying my improvements, and of a detached cockpit of a rowing boat combined therewith; one of the friction straps is shown in its inoperative position. Fig. 2 shows, on an enlarged scale, an end view of the exercising machine shown at the right in Fig. 60 1, looking in the direction of arrow *a*, same figure; the cords and handles are shown in their inner position, as shown by broken lines in Fig. 1. Fig. 3 is a central vertical section, on line 3, 3, Fig. 2, looking in the 65 direction of arrow *b*, same figure. Fig. 4 is a section, on line 4, 4, Fig. 3, looking in the direction of arrow *c*, showing the operating spring in its extended position, when the cords and handles are in their inner position; the handle on the cord is not shown, and, Fig. 5 corresponds to Fig. 4, but shows the operating spring in its contracted position, when the cords and handles are fully drawn out, preparatory to being returned by 70 the expansion of the spring.

In the accompanying drawing, 1 is the frame of the exercising machine, which is preferably made of cast metal, and has the base 1', which, in this instance, has attached 80 to its rear edge two hooks or attaching devices 2, adapted to be connected with screw eyes, or other devices, for holding the exercising machine in position. Any suitable means may be employed for securing the 85 base 1' of the exercising machine in the desired position, either on the floor, or on the wall.

The frame 1 has the central upright stand 1'', on each side of which, and preferably integral therewith, is an annular recessed portion or chamber 1'''. The central stand 1'' has a transverse opening therethrough, and forms a bearing for the shaft 3. On the shaft 3 are mounted two 90 rotary drums, which are of similar construction. Each drum 4 has a hub 4', which is loosely mounted on the shaft 3, and in this instance held in place thereon by a washer 5, and a bolt or screw 6 at each end of the 95 shaft 3. The hub 4' of each rotary drum 4 extends within the annular chamber 1''' on the frame 1. Each drum 4 has its periphery grooved or recessed to receive a cord 7,

which is wound around said drum, and attached at one end thereto. To the free end of the cord 7 is attached a handle 8, which may be of any ordinary construction. Extending within each annular chamber 1''' is, in this instance, a spirally coiled flat motor spring 9, which is attached at one end to the wall of the chamber 1''', as shown in Figs. 4 and 5, and at its other end to the hub 4' 10 of the drum 4. Extending out from each drum 4 is, in this instance, an annular lip or flange 4'', around which passes a strap of leather, or other suitable material 10, which, in this instance, has a hook 10' attached to one end which is attached to a stand 11, secured in this instance to the base 1'. The other end of the strap 10 has a pin 12 secured thereto, which passes loosely through an opening in the stand 11, and has 15 a threaded end, on which is mounted a thumb nut 13. A helically coiled expansion spring 14 extends between said nut 13 and the stand 11. By turning in or out the nut 13, on the pin 12, the friction of the strap 10 on the annular flange 4'' on the rotary drum 4, is increased or diminished as desired.

On the top of the stand 1'' is secured, by bolts 15, a plate 16 which has thereon a bar 16', having oppositely extending arms 16'', which extend over the recessed peripheries of the rotary drums 4 at the rear part of the machine, and are preferably curved on their inner edge, as shown in Fig. 1. The oppositely extending arms 16'' act to limit the inward movement of the handles 8, and to hold them in their inward position, as shown by broken lines in Fig. 1, and by full lines in Fig. 2. The oppositely extending arms 40 16'' also act to hold the cords 7 on the pulleys 4, and to guide said cords and prevent them from running off the pulleys.

In connection with my exercising machine above described, I may use a detached cock 45 pit of a rowing boat, to obtain the results of a rowing machine. The cock pit may be of any ordinary construction, and as shown in Fig. 1 consists of the track 17, shown broken away at the left, for the sliding seat 50 18. The track 17 is in this instance supported upon and attached at one end to a transverse bar 19, which is secured to a central bar or support 20. The front end of the bar 20 is adapted in this instance to extend 55 through the opening 1^a in the upright stand 1'' on the frame 1 of the exercising machine, and is detachably secured to the frame of the machine by bolts, or otherwise. 21 are two foot rests, which are attached to 60 a transverse bar 22 secured to the central bar 20, and are provided with foot straps 23, in the ordinary way.

From the above description in connection with the drawing, the operation of my ex-

ercising machine may be readily understood by those skilled in the art. If it is desired to use the machine without the rowing attachment, the bar 20 of the cock pit is detached from the frame 1 of the exercising machine. The base 1' of the exercising machine is secured to the wall, or to the floor of a room, to hold it in a fixed position. If it is desired to use the machine for light exercise, or for children, the friction straps 10 are loosened, or detached from the rotary drums by moving them outwardly, as shown in the upper part of Fig. 1. The handles 8 are grasped by the hands of the user, and are drawn out together, or separately, as desired, to unwind the cord 7 from the rotary drums, against the action of the spring 9 connected with each drum, to wind up said spring 9, see Fig. 5. The unwinding of the spring 9 will return the cords 7 and handles 8 to their inner position, see Fig. 4. When it is desired to increase the friction on the drums, the strap 10 is replaced, and the nut 13 turned in on the pin 12. When it is desired to use the exercising machine as a rowing machine, the cock pit, shown in Fig. 1, is attached to the frame 1 of the exercising machine, and the exercising machine is used in the same manner as above described, the user sitting on the sliding seat 18 with his feet in the foot rests 21.

By my construction of an exercising machine, a great variety of movements of the arms may be obtained with the cords and handles, and also a great variety of movements of the body, and the cords may be operated by the feet of the user, by placing the toe part of the foot within the handle, to obtain a variety of movements of the legs. The movement of the legs is also obtained in using the exercising machine in connection with the cock pit of a rowing boat.

It will be understood that the details of construction of my improvements may be varied if desired. Instead of two rotary drums, one rotary drum may be used with good results.

Having thus described my invention, what I claim as new and desire to secure by Letters Patent is:

1. In an exercising machine, the combination with a portable frame or stand, adapted to be secured in position, and a shaft mounted on said frame, of two rotary drums mounted on said shaft, each drum having a cord wound around the same, and connected therewith, and a spring connected with each drum, and also with said frame, to control the rotary motion of each drum, and means to guide said cord and hold it on each drum, and to stop the winding of said cord on each drum.

2. In an exercising machine, the combination with a portable frame or stand, adapted

to be secured in position, and a shaft mounted on said frame, of a rotary drum mounted on said shaft, said drum having a cord wound around the same and connected therewith, and a spring connected with said drum, and also with said frame, to control the rotary motion of said drum, and means

to guide said cord and hold it on said drum, and stop the winding of said cord on said drum.

EDWARD J. KERNS.
